CLAIM

The ornamental design for a motor car body, toy car body replica and/or other replica, as shown and described.

DESCRIPTION

FIG. 1 is a top, front and left side perspective view of a motor car body, toy car body replica and/or other replica showing my new design;

FIG. 2 is a top, rear and left side perspective view thereof;

FIG. 3 is a top view thereof;

FIG. 4 is a left side view thereof;

FIG. 5 is a right side view thereof;

FIG. 6 is a front view thereof;

FIG. 7 is a rear view thereof; and,

FIG. 8 is a bottom view thereof.

The portions of the motor car body shown in broken lines are for environmental and illustrative purposes and form no part of the claimed design.

1 Claim, 8 Drawing Sheets
